UNITED STATES PATENT OFFICE.

JOSEPH B. McMULLIN, OF OSKALOOSA, IOWA, ASSIGNOR TO WESTERN MANUFACTURING CO., OF OSKALOOSA, IOWA, A CORPORATION OF IOWA.

HOSE-REEL.

1,389,314.

Specification of Letters Patent. Patented Aug. 30, 1921.

Application filed August 13, 1919. Serial No. 317,294.

To all whom it may concern:

Be it known that I, JOSEPH B. McMULLIN, a citizen of the United States, residing at Oskaloosa, in the county of Mahaska and State of Iowa, have invented a new and useful Hose-Reel, of which the following is a specification.

This invention has reference to hose reels, and its object is to provide a reel and hose particularly adapted for use in connection with supplying air under pressure for the inflation of automobile tires, but is at the same time susceptible of other uses.

The invention comprises a hose reel and stand therefor, which stand may be of a character to permit it being located at or adjacent to a street curb so that the hose may be withdrawn from the reel for the purpose of connecting the hose to automobile tires for inflating them, the arrangement being such that on releasing the hose the latter will automatically re-wind upon the reel in accessible but protected position. Ordinarily the hose is under the control of locking means whereby indiscriminate use of the hose is prevented and by providing a coin lock the assurance is had that the hose will only be used as needed and not be open to malicious use.

In order that the public may be notified of the service provided, a suitable sign, visible either in daylight or at night, may be carried by the stand and in addition thereto a gage is provided indicating the air conditions available.

The invention will be best understood from a consideration of the following detailed description taken in connection with the accompanying drawings forming part of this specification, with the understanding, however, that the invention is not confined to any strict conformity with the showing of the drawings, but may be changed and modified so long as such changes and modifications mark no material departure from the salient features of the invention as expressed in the appended claims.

In the drawings:—

Figure 1 is an elevation of the hose reel stand.

Fig. 2 is a vertical front to rear section of the upper portion of the stand and drawn on a larger scale than Fig. 1.

Fig. 3 is a view similar to Fig. 2 but con-

tinued through the stand to the base thereof and on the same scale as Fig. 2.

Fig. 4 is a vertical axial section of the hub portion of the reel and parts adjacent thereto and drawn on a still larger scale than Fig. 3.

Fig. 5 is a section on the line 5—5 of Fig. 4.

Fig. 6 is an elevation of a coin-controlled mechanism useful in connection with the hose reel.

Figs. 7, 8 and 9 are detail views of the structure shown in Fig. 6.

Fig. 10 is a longitudinal section on a larger scale than some of the other figures, showing a valve structure for admitting air to or cutting it off from the hose.

Fig. 11 is a section on the line 11—11 of Fig. 10.

Fig. 12 is a section on the line 12—12 of Fig. 10.

Referring to the drawings there is shown a base 1 which may be a casting of any suitable shape or be otherwise formed than by casting. The base 1 is designed to be mounted on a pavement near a curb or at any other suitable point. Rising from the base 1 is a column 2 which may also be a casting or be of other suitable formation and this column merges into a casing 3, which, being intended to house a hose reel 4, is of cylindrical shape in most part, to avoid waste of material, although the hose reel casing 3 need not necessarily be of such shape. Moreover, the casing 3 may be offset laterally with respect to the column 2, because of certain parts which are located within the column to one side of the hose reel 4. Various mechanisms are located within the column 2 and casing 3, and for convenience of manufacture and to properly protect such mechanisms as well as to render them readily accessible when desired, the body of the casing 3 has one side left open and this side is closed by a face plate 5 conveniently held in place by screws 6 or other suitable fastening means. The opposite face plate of the casing 3 is indicated at 7 in Figs. 3 and 4 and may constitute an integral part of the casing. The plate 7 is provided with an axial stud 8 from which there projects an arbor 9 in fixed relation to the stud and extending toward the other face or cover plate 5. Mounted on the ar-

bor 9 is a hub 10 carried by roller bearings 11 between the hub and the arbor. One end of the hub has an inturned flange 12 for confining a set of roller bearings 10 and there is another set of such roller bearings near the opposite end of the hub, separated from the first-named set by a spacing sleeve 13.

The outer end of the hub 10 is internally screw-threaded to receive a hollow plug 14 10 and this plug is closed at the outer end by another plug 15 leaving a chamber 16 between the two plugs. At one side of the plug 14 there is formed a nipple 17 to which is screwed a pipe 18. The arbor 9 is provided 15 with an axial passage or bore 19 extending throughout the greater portion of its length and opening at the outer end of the arbor close to the plug 14. Screwed into or soldered in the open end of the bore 19 is a pipe or 20 tube 20 extending into the chamber 16 through the base of the plug 14 and packed, where passing through the bottom of the plug 14, by suitable packing material 21 held in place by a gland 22. In this way the 25 hub 10 may readily rotate about the arbor 9 without danger of leakage between the bore 19 and the chamber 16 and with free passage of air from the bore to the chamber. Formed on the hub is a radial circumferential flange 23 carrying an annulus 24 forming one face plate of a hose reel. Attached to the face plate 24 by means of rivets 25 and spacers 26, or in any other suitable manner, is another annulus 27 forming the 30 opposite face plate or wall of the hose reel. The arrangement is such that the hose reel is supported by the one flange 23, although formed of two spaced face plates so located as to receive a hose 28 between them.

40 When the hose is wound on the reel it forms a spiral as is customary. One end of the hose is extended through and held by a lip 29, shown in Fig. 3, while the other end of the hose carries a nipple connection 30 45 such as shown, described and claimed in my application Number 310,144, for tire pump connection, filed July 11, 1919.

The casing 3 is provided at a suitable part of it, say, at the upper portion near one side, 50 with an outstanding neck 31 through which the hose 28 is carried, and a ball 32 or other stop means on the hose outside of guiding and retaining rollers 33 in the neck 31 prevents the complete indrawing of the hose 55 into the casing 3 and also avoids injury to the nipple connection 30, leaving the latter exposed to an extent permitting it to be grasped by the hand of the user. The pipe 18 at the end remote from the plug 14 is connected to the inner end of the hose 28 in a 60 manner that the pipe 18 and hose 28 are always in communication. Since the pipe 18 rotates with the hose reel such connection is never broken and no strain occurs on the 65 parts.

The hub 10 is provided with a circumferential series of gear teeth 34 which are elongated in the direction of the length of the hub to facilitate the making of the casting. At one point the continuity of the teeth is 70 broken by a circumferential groove 35 to accommodate a circumferentially elongated tongue 36 formed on the inner surface of a shield 37 overlying the gear teeth on the hub. This shield is made fast to the stud 8 75 by screws 38 or otherwise. Meshing with the gear teeth 34 is a gear wheel 39 carried by a drum 40 inclosing a spiral spring 41. The drum 40 with the spring 41 is mounted upon a hub 42 in turn carried by a spindle 80 43 projecting from a boss 44 on the inner face of the plate 7. The arrangement is such that as the hose is withdrawn from the hose reel the hub 10 is rotated and through the gear teeth 34 and gear wheel 39 the spring 85 41, which latter, when the device is originally installed, is placed under some tension, at least sufficient to retract the hose after having been pulled out from the casing 90 3 for use. One face of the drum 40 is provided with a spiral groove 45 shown in Figs. 3 and 4 and in this groove there is engaged a pin 46 projecting from one arm 47 of a lever 48, the pin 46 being located about midway of the length of the arm 47. Formed on the grooved face of the spring drum 40 is a socket 49 containing a compression spring 50 serving as a buffer, this spring being in the path of the pin 46 at one limit of its 100 movement along the groove 45. When the hose 28 is fully retracted the pin 46 is at the socket 49 and engaging the spring 50 lodged therein. Under these circumstances the extremity of the arm 47, which is then in 105 nearly upright position with the pivot or fulcrum of the arm uppermost, is at the limit of its movement toward the left as seen in Fig. 3. When the hose is withdrawn from the reel, the spring drum is given a clockwise movement thereby causing the groove 45 to propel the pin 46 and with it the arm 47 toward the right. A stop 51 in the column 2 limits the movement of the arm 47 110 toward the left in Fig. 3. In the path of the outer or lower end of the arm 47, which end is provided with an antifriction roller 52, is a beveled extremity 53 of one arm 54 of a rock lever 55 having the other or short arm 56 at an angle to the long arm 54 so that the lever 55 is in the nature of a bell-crank lever.

The purpose of the lever 55 is to cause the actuation of a valve structure 57 shown on a small scale in Fig. 3 and on a larger scale 125 in Figs. 10, 11 and 12, to which reference is particularly had in the following description of such valve. The valve 57 comprises a casting including two chambers 58 and 59 respectively, which may be arranged side by 130

side for convenience of construction and compactness. The chamber 58 is permanently closed at one end and at the other end is closed by a screw plug 60. The interior of the chamber is provided with a series of circumferential grooves 61 all joined along the side toward the chamber 59 by a groove 62. Within the chamber 59 there is lodged a cylindrical screen 63 including all the grooves 61 and at one end opening through a port 64 into a pipe connection 65 to which a pipe 66 is made fast. The pipe 66 is intended to and may be assumed to be connected to a source of air under compression, such as is provided at the usual air stations. The chamber 58 is connected to the chamber 59 through a port or passage 67 intermediate of its length. Within the chamber 59 there are located two washers or packing members 68 and 69 respectively. The packing member 69, which may be in the form of a rubber washer, is lodged against a shoulder 70 formed in the wall of the chamber 59 and the packing member 68 is lodged against a screw plug 71 forming a closure for the corresponding end of the chamber 59. The two washers 68 and 69 are separated by a spacing sleeve 72 which also serves in connection with the plug 71 to tightly lodge the two washers in the chamber 59 against the possibility of leakage by them. The spacing sleeve 72 has an exterior circumferential groove 73 and this groove is connected with the interior of the sleeve at intervals by passages or ports 74 so that the interior of the sleeve has free communication with the groove 73. Through the wall of the chamber 59 there is a port or passage 75 with which there communicates a pipe 76 ultimately connected to the bore 19 of the arbor 9, as shown in Fig. 4. Extending through the plug 71 is a rod 77 also extending through the packing washers 68 and 69 into that end of the chamber 59 with which the port 67 communicates. The washer 69 has a conical face 78 forming a valve seat for a valve 79 engaged by the neighboring end of the rod 77. The valve 79 is constantly urged toward the valve seat 78 by a compression spring 80 between the valve and the inner wall of the chamber 59 remote from the plug 71. The last-named end of the chamber 59 has a port 81 therethrough terminating in a nipple 82 which, by means of a coupling 83, is made fast to a pipe 84, which latter, as shown in Figs. 2 and 3, is carried up through the casing 3 and into a post 85 to a pressure gage 86 near the upper end of the post and so arranged as to be readily visible to an observer who may at any time ascertain the pressure within the pipe 84. The post 85 is surmounted by a globe 87, which may be of glass or other suitable light-transmitting material, containing insignia 88 to indicate the purpose of the whole structure. In the special instance shown in the drawings, the insignia consists of the words "Air service" thereby informing the reader that air for charging tires or the like may be obtained from the device. Within the globe 87 there is contained an electric lamp 89 fed by current delivered through a conducting cord 90 coming from any suitable source of electric supply.

The end of the rod 77 outside of the chamber 59 has a screw-threaded portion 91 carrying a nut 92 which may be utilized as an abutment for the arm 56 of the lever 55 so that when the lever 55 is actuated by the arm 47 the rod 77 is moved through the washers 68 and 69, causing a like movement of the valve 79.

The rod 77 adjacent to the end engaging the valve 79 has a longitudinal bore 93 with branches 94 and 95 leading to the exterior of the rod. The branch 94 opens into the interior of the spacing sleeve 72. The branch 95 opens into the interior of the valve 79 which is chambered for the purpose. Whenever the valve 79 is opened there is communication between that portion of the chamber 59 communicating with the pipe 84 and the pipe 76. In this manner air under pressure from the source of compressed air may be conducted, when the valve 79 is opened, into the chamber 58 through the screen or strainer 63, thus preventing anything but clean air entering the chamber 58 within the screen 63. This air then passes by way of the port 67 into the compartment 59 from which the clean air passes by the valve 79 through the ports 95, 93 and 94 respectively, to the pipe 76 which finally conveys the air to the hose, and, assuming that the latter is withdrawn and applied to the valve nipple of an automobile tire, the air is conducted into the tire. Reservoir air pressure is indicated on the gage 86 by way of the tube or pipe 84, chamber 59, passage 67, chamber 58 and pipe 66.

While the lever 48 may be actuated or controlled in any suitable way, by hand or otherwise, it provides a convenient means whereby coin-controlled mechanism may be utilized, such mechanism being best shown in Figs. 6 to 9 inclusive.

At a suitable point within the casing 3 is located a compartment 96 entered by and containing a coin chute 97. The coin chute in the particular showing of the drawings is upright, although this is not at all obligatory, and below the coin chute there is located a stud 98. Mounted on the stud is one end of a pendent rock arm 99 having an angle extension or finger 100 normally so situated as to be in line with a series of notches 101 in the outer margin of the face plate or annulus 24, whereby the face plate 24 is in effect a ratchet wheel and the finger 100 serves as a ratchet acting as a stop pre-

venting rotation of the hose reel in one direction but permitting it to rotate freely in the other direction. Mounted on the stud 98 is a rock lever 102 shown separately in Figs. 7 and 8. The lever 102 has a passage or perforation 103 about midway of its length fitting the stud 98. At one end the lever 102 is provided with an expanded plate-like head 104 with a perforation or passage 105 there-through. At the other end the lever 102 has an angle extension 106 from the extremity of which there is an angular projection 107. Adjacent to the projection 107 the extension 106 carries a stud 108 serving as a pivotal 15 mounting for a latch plate or trigger 109 held to the stud by a screw 110 or otherwise. The latch plate 109 is held yieldably in a desired position by a spring 111 and adjacent to the spring carries a laterally 20 projecting pin 112. The arm 99 is connected to the lever 102 by a spring 113.

Mounted in the compartment 96 so as to project through the wall of the casing 3 is a push-button 114, having a stem extension 25 115 projecting into the chute 97 but normally out of the path of a coin inserted in the chute. A spring 116 on the stem of the push-button 114 is arranged to hold the latter in the normally projected position accessible to an operator. The stem extension 115 is in line with the passage 105.

The lever 48 has an arm 117 at an angle to the arm 47 and said arm 117 terminates in a laterally expanded cam head 118 extended into the compartment. Fast to the hub 42 to which the spring 41 is secured, is an arm 119 whereby the initial tension of the spring 21 may be adjusted. To hold the arm 119 in any desired position of adjustment, 35 the free end of the arm carries a screw 120 capable of setting in any one of a series of perforations or sockets 121 in the casing 3.

In considering the operation of the hose reel structure, it may be assumed that the 45 structure is mounted in accessible position, say, adjacent to a street curb and that the spring 41 is suitably adjusted and the hose 28 is wound on the reel within the casing 3 with only the nipple connection or chuck 30 exposed for access. If, now, a person desires to use the hose for inflating a tire, a suitable coin is dropped into the coin chute 97 and its progress is arrested opposite the head 104 of the lever 102 in the path of the 50 stem or extension 115 of the push-button 114. If no coin be introduced the push-button may be manipulated, and the stem 115 will pass freely through the perforation 105 and perform no function. With the coin in place, 55 pushing on the button 114, causes the coin to engage the head 104 and thereby rock the lever 105 against the action of the spring 111. The lever 102 engages a lug 122 on the arm 99, thus rocking the latter in a direction 60 to clear the finger 100 from the particular

notch 101 in which the finger rested, so that the hose reel is no longer locked but may be freely turned. As the lever 102 is moved in the manner described the latch plate or trigger 109 is brought into engagement with another lug 123, thereby holding the arm 99 and lever 102 in the position to which they have been moved by the push-button 114, and on release of the push-button it is returned to the first or projected position by the 70 spring 116. The coin originally engaged by the push-button then drops through a slot 124 out of line with the coin chute and may find lodgment in a suitable coin box. The hose reel being thus released permits the 75 withdrawal of the hose to any needed extent and the rotation of the hub 10 causes the winding of the spring 41 through the intermediary of the teeth 34 and the gear wheel 39. As the unwinding of the hose 80 proceeds with the corresponding winding of the spring 41, the spiral groove 45 on the spring drum, by engaging the pin or stud 46 on the arm 47 causes the roller 52 to ride along the beveled edge 53 of the arm 54 of the lever 55, thereby rocking the arm 56 in the direction to move the rod 77 sufficiently to open the valve 79. Now, air under pressure coming from a suitable reservoir, not shown, through the pipe 66, may flow into 85 the chamber 58 and out therefrom through the port 67, being in the meantime cleansed or filtered by the strainer 63. A portion of the air flows by way of the port 81 through the pipe 84 to the gage 86, 90 thus indicating the air pressure. Another portion 81 of the air passes around the valve 79 through the ports 95, 93 and 94 to the pipe 76, and thence to the passage 19, tube 20, chamber 16 and pipe 18 into the 95 hose 28. However, the air cannot escape from the hose because of the presence of the chuck or nipple coupling 30. This chuck is of a character permitting the passage of air 100 from the hose into the inner tube of the tire 105 when applied to the inner tube nipple, but automatically closes as soon as the chuck is removed from the inner tube nipple. During this time the hose is held extended 110 against the pull of the spring 41. As soon as the operator is finished with the hose he has but to let go of it, whereupon, the expansion of the spring 41 causes a turning of the hose reel and a rewinding of the hose 115 thereupon until further movement of the 120 hose is stopped by the engagement of the enlargement 32 with the rollers 33. The rewinding of the hose causes the reverse movement of the arm 47 of the lever 48 and a corresponding reverse movement of the arm 117 125 and the head 118, which latter then engages the latch plate or trigger 109 and releases it from the stop 123, thus permitting the lever 102 to return to its first position and the arm 99 to also return to its first position together 130

with the lever 102. The finger 100 is, by this operation, moved into a notch 101 thereby preventing a re-withdrawal of the hose from the reel and lock the parts all in the first position from which they may be released only by the deposition of another coin.

While the gage 86 and lamp 89 may be supported in various ways it is preferred to provide a lug 123 projecting inwardly in the column 85 and this lug is provided with a passage to accommodate the bolt 124 threaded into the back of the casing of the gage 86, thereby holding the latter in the column. A lock nut 125 serves to hold the parts firmly together and also to clamp one leg of an angle bracket 126 to the lug 123, the angle bracket being long enough to rise into the globe 87 and there support the lamp socket 127 in turn receiving the electric lamp 89.

While the hose reel structure has been described as useful in connection with air hose, it is to be understood that it may be used in connection with hose carrying other fluids than air, although it is particularly useful in connection with service stations or garages where air under pressure is customarily provided for the inflation of automobile tires.

The valve structure shown more particularly in Figs. 10, 11 and 12, and also appearing in Fig. 3, forms the subject matter of and is claimed in another application, Serial No. 404,071, filed August 17, 1920, for valve device for hose reels, and constitutes a division of this application.

What is claimed is:—

1. In a hose reel structure, a hose reel provided with a hub having gear teeth thereon with a circumferential groove in the gear teeth, a spindle carrying the hub, a spring drum with a gear wheel thereon engaging the gear teeth, and a shield overlying the gear teeth and provided with a tongue entering the groove in the gear teeth to hold the hub on the spindle.

2. A hose reel structure, comprising an upstanding basic member, an arbor projecting laterally from the basic member, a hose reel having a hub mounted on the arbor and provided with gear teeth thereon, a spring drum carried by the support at one side of the arbor and having gear teeth meshing with the gear teeth on the hub, a spring in the drum having a constant tendency to hold the hose taut when withdrawn from the drum, manipulating means connected to the spring in coactive relation to the support for varying the tension of the spring, and fluid conducting means for conducting fluid under pressure to hose on the reel.

3. A hose reel structure comprising a suitable support, a hose reel carried by the support and provided with a hub having gear

teeth thereon, a spring drum with a spring therein also carried by the support and provided with a gear wheel meshing with the gear teeth on the hub, and means connected to the spring in coactive relation to the support for varying the tension of the spring, said last-named means comprising a hub to which one end of the spring is connected and an arm fast to the hub and attachable to the support in different positions about the axis of the hub.

4. In a hose reel structure, a rotatable reel for hose connected to and actuated by hose on the reel, a spring drum geared to the reel for causing winding of a spring in the drum by withdrawal of the hose on the reel, said spring drum having a spiral thereon, a lever engaging the spiral for actuation of the lever by rotative movements of the spring drum, and a valve responsive to movements of the lever and provided with means for connecting it to a source of fluid under pressure, said valve being connected to the hose for delivering fluid under pressure thereto.

5. A hose reel comprising a drum for holding a coil of hose, a spring drum with a spring therein and connected to the hose for winding the spring by unwinding the hose, a spiral on the spring drum terminating at one end in an elastic buffer, a valve controlling the flow of fluid under pressure to the hose, and actuating means for the valve in turn engaging and actuated by the spiral, the buffer being arranged in the path of the actuating means for the valve.

6. A hose reel structure comprising a rotatable drum for containing a coil of hose, a spring drum containing a spring and connected to the hose drum for winding the spring by withdrawing the hose from the drum, a valve for admitting fluid under pressure to the hose, and means for controlling the valve comprising a rock lever with one end directly controlling the valve, another rock lever engaging the first-named rock lever and movable in a different direction from said first-named rock lever to cause the first lever to be moved by the second lever, and a spiral on the spring drum controlling the second-named lever.

7. A hose reel structure comprising a rotatable drum for containing a coil of hose, a spring drum containing a spring and connected to the drum for winding the spring by withdrawing the hose from the drum, a valve for admitting fluid under pressure to the hose, and means for controlling the valve comprising a rock lever with one end directly controlling the valve, another rock lever engaging the first-named rock lever and movable in a different direction from said first-named rock lever to cause the first lever to be moved by the second lever, and a spiral on the spring drum controlling the second-named lever, one of the levers hav-

ing a beveled surface engaged by the other lever to produce a change in direction of movements of the levers.

8. A hose reel structure comprising a rotatable drum for carrying the hose, said drum being provided with a hub with gear teeth thereon, a spring drum with a gear wheel thereon engaging the gear teeth on the hub of the reel, said spring drum being provided on one face with a spiral terminating at one end in an elastic buffer, a rock arm provided with a pin engaging the spiral with the elastic buffer in the path of the pin, a lever having a beveled end in the path of the rock arm for engagement and actuation by the latter, and a valve controlled by the lever for in turn controlling the passage of fluid under pressure from a reservoir thereof to the hose.
10. A hose reel structure comprising a rotatable drum for a coil of hose, a spring drum, gearing connections between the spring drum and the drum for the hose, said spring drum having a spiral on one face thereof, a rock arm engaging the spiral at a point intermediate of the length of the arm, a reciprocating valve for controlling the passage of fluid under pressure from a supply thereof to hose on the reel, and a rock lever for actuating the valve and in turn actuated by the rock arm.
12. A hose reel structure comprising a rotatable hose-carrying drum with a peripheral series of detent devices, a rock arm having a nose projection normally constrained to engage a detent device to hold the reel against rotation in one direction, manually operable means for releasing the hose reel for rotation in the opposite direction, a valve device for controlling the flow of fluid under pressure to a hose on the reel, a rock lever for controlling the valve device and in turn controlled by the manually operable means, and means under the control of the hose reel for causing movements of the rock lever to open and close the valve.
14. A hose reel structure comprising a rotatable drum for the hose, a spring drum connected to the hose drum for winding the spring by withdrawing the hose from the hose drum, said spring drum having a spiral on one face, a valve device for controlling the flow of fluid under pressure to the hose, a lever structure for actuating the valve device and connected to and controlled by the spiral on the spring drum, means for locking the drum against rotation in one direction, said means also controlling the lever structure, and manually operable means for releasing the drum and lever structure to operation by the withdrawal of the hose from the hose reel.
16. In a hose reel structure, a hose reel provided with a hub having a circumfer-

tial series of axially elongated gear teeth, 65 with the latter provided with a circumferential groove near one end, a spring drum carrying a gear wheel meshing with the gear teeth on the hub, a spindle on which the hub is mounted, and a tongue carried 70 by a fixed part of the structure and entering the groove to hold the reel on the spindle.

13. A hose reel structure comprising a suitable support, a hose reel carried thereby, a spring drum with a spring therein also carried by the support, connections between the hose reel and spring drum for causing one to move the other, and means connected to the spring drum in coactive 80 relation to the support for varying the tension of the spring, said means comprising a hub to which one end of the spring is connected and an arm fast to the hub, the support and arm having coacting means for 85 securing the arm to the support in different positions to thereby vary the tension of the spring.

14. A hose reel comprising a drum for holding a coil or hose, a spring drum with 90 a spring therein and connected to the reel for winding the spring by unwinding the hose, a spiral groove on the spring drum having an elastic buffer seated at one end, a valve for controlling the flow of fluid under 95 pressure to the hose, and actuating means for the valve engaging in and actuated by the spiral groove with the buffer in the path of the valve-actuating means in the direction in which the latter is moved 100 by the spring.

15. A hose reel structure comprising a rotatable drum for containing a coil of hose, a spring drum containing a spring and connected to the hose drum for winding the 105 spring by withdrawing the hose from the drum, a valve for admitting fluid under pressure to the hose, and means for controlling the valve comprising an angle lever with one end directly controlling the valve, 110 a rock arm engaging the angle lever at the end remote from that engaging the valve, the end of the rock arm engaging the angle lever having a range of movement lengthwise of the portion of the angle lever engaged by the rock arm, with said angle 115 lever beveled where engaged by the rock arm, and a spiral on the spring drum engaging and controlling the rock arm to cause movement thereof in a direction to actuate the angle lever.

16. A hose reel structure comprising a rotatable drum for containing a coil of hose, a spring drum containing a spring and connected to the hose drum for winding the 125 spring by withdrawing the hose from the drum, a valve for admitting fluid under pressure to the hose, and means for con-

trolling the valve comprising two levers in angular relation with the pivot supports of the levers spaced apart and the ends of the levers remote from the pivots engaging, 5 one lever controlling the valve and the other lever controlled by the spring drum, whereby the valve is responsive to the with-

drawal of the hose from the hose drum and the return of the hose onto said drum.

In testimony that I claim the foregoing 10 as my own, I have hereto affixed my signature.

JOSEPH B. McMULLIN.
